(57) **CLAIM**

The ornamental design for a safety cone for warning of slippery conditions, substantially as shown and described.

DESCRIPTION

A Safety Cone which is especially useful and effective as a warning regarding risks of slipping, simulates a partially peeled banana and is to be disposed on slippery surfaces. FIG. 1 is a perspective view of a safety cone for warning of slippery conditions showing my new design;

FIG. 2 is a front elevation view of the safety cone of FIG. 1,

FIG. 3 is a top plan view of the safety cone of FIG. 1;

FIG. 4 is a bottom plan view of the safety cone of FIG. 1; and,

FIG. 5 is a cross sectional view taken along line 5—5 of FIG. 4.
